FIG. 4

INVENTOR.
Prospero Donadio,
BY Charles R. Searle,
ATTORNEY.

UNITED STATES PATENT OFFICE.

PROSPERO DONADIO, OF BROOKLYN, NEW YORK.

SAFETY-LOCK FOR REVOLVERS.

1,313,073.

Specification of Letters Patent. Patented Aug. 12, 1919.

Application filed May 31, 1919. Serial No. 301,062.

To all whom it may concern:

Be it known that I, PROSPERO DONADIO, a subject of the King of Italy, residing in the city of New York, borough of Brooklyn, 5 in the county of Kings and State of New York, have invented a certain new and useful Improvement in Safety-Locks for Revolvers, of which the following is a specification.

- 10 The invention relates to means for holding the hammer against operative movement until intentionally released, and the object of the invention is to provide a simple locking device of few parts, reliable and 15 positive in its action, and easily added to the frame and firing mechanism of the revolver in the process of manufacture, by which the hammer is held against rising until freed by pressure of the hand automatically in grasping the butt of the revolver with the force required by the act of 20 firing.

The invention consists in certain novel features and details of construction and arrangement by which the above objects are attained, to be hereinafter described and claimed.

The accompanying drawings form a part of this specification and show the invention 30 as it has been carried out in practice.

Figure 1 is a side view of a double action revolver, partly in vertical section and with certain portions broken away or omitted, equipped with the improved safety-lock, 35 shown in the locked condition.

Fig. 2 is a similar view of the rear portion of the same, showing the unlocked condition, in the act of firing.

Fig. 3 is a rear view of the revolver.

40 Fig. 4 is a vertical section of the locking lever and its connections, partly in elevation.

Similar letters of reference indicate the same parts in all the figures.

45 A is the frame of the revolver, B the hammer mounted on the hammer-screw A¹, and C the mainspring having its free end engaged in the notch b of the hammer and acting thereon as usual. The hammer is 50 raised in opposition to the mainspring through the trigger D by the usual or any approved means.

In the cheeks A² of the frame is a pin E serving as the fulcrum for the locking 55 dog or lever F by which the hammer is held against rising. It has a nose F¹ shown

as presented to the rear face of the hammer in the notch b adjacent the concentrically curved portion B¹ of the hammer, and its tail lying adjacent the rear limb A³ of the frame A between such portion of the frame and the mainspring C.

A light helical expansion spring F³ mounted in a recess f in the locking lever near its lower end, abuts against the mainspring C and exerts its force to hold the tail F² of the lever against the inner face of the limb A³, and the nose F¹ in the path of the portion B¹ of the hammer and thus prevent the rising movement of the latter.

The tail F² carries a stud F⁴ projecting through the limb A³ of the frame, having a flat head or plate F⁵ on the protruding end, held out of contact with the rear face of the limb by the action of the spring F³.

In exerting the pull required by the trigger finger in raising the hammer, the hand forces the plate F⁵ toward the limb A³ of the frame, compresses the spring F³ and tilts the lever sufficiently to swing the nose F¹ clear of the hammer and permits the hammer to complete its firing movement. On releasing the plate the lever is returned to the engaged position through the force of the spring F³.

The revolver cannot be fired until the locking lever is thus tilted, and the plate F⁵ is so located as to produce the required tilting movement automatically in the act of firing.

The lever with its pin E, spring F³, stud F⁴ and plate F⁵ is easily added to the revolver in the process of manufacture without change other than the production of the perforations required for the pin and stud, and consequently adds but little to the cost of production, and is applicable to many types of revolvers, with or without slight modifications as may be found necessary in such adaptations.

It will be noted that the pressure on the plate F⁵ need be maintained only long enough to free the nose F¹ from the hammer; in the further rising movement of the hammer the nose rides upon the concentric portion B¹ thereof, see Fig. 2, and is inoperative until the hammer falls.

The size and shape of the plate F⁵ may be varied as found necessary or desirable.

I claim:—

1. The safety-lock described, comprising a lever fulcrumed in the frame of the re-

revolver, having a nose adapted to engage the hammer and prevent the rising movement of the latter, a spring on said lever abutting against the mainspring of the revolver and 5 tending to hold said nose yieldingly in such engagement, and means on said lever extended through the rear portion of said frame for tilting said lever by pressure.

2. The safety-lock described, comprising 10 a lever fulcrumed in the frame of the revolver, having a nose adapted to engage the hammer and prevent the rising movement of the latter, a spring on said lever

abutting against the mainspring of the revolver and tending to hold said nose yieldingly in such engagement, a stud on said lever extending through the rear portion of said frame, and a plate on said stud adapted to be acted upon by pressure to tilt said lever. 15

In testimony that I claim the invention above set forth I affix my signature. 20
